UNITED STATES PATENT OFFICE.

MARQUIS H. LOCKWOOD, OF NEW YORK, N. Y., ASSIGNOR TO UNDERWOOD TYPE-WRITER COMPANY, A CORPORATION OF DELAWARE.

TYPE-WRITING MACHINE.

1,158,819.

Specification of Letters Patent.

Patented Nov. 2, 1915.

Application filed August 9, 1913. Serial No. 783,867.

To all whom it may concern:

Be it known that I, MARQUIS H. LOCKWOOD, a citizen of the United States, and resident of the borough of Manhattan, city, 5 county, and State of New York, have invented certain new and useful Improvements in Type-Writing Machines, of which the following is a specification.

My invention relates to typewriter platen releases which are adapted to normally secure the platen and line space wheel together so that they may be revolved in unison, but which permit the operator, by manual means, to free the platen from the line space 15 wheel and revolve it independently thereof.

Devices of various kinds have been constructed for this purpose which are more or less satisfactory, but my invention relates more particularly to improvements in that 20 type of platen releases employing an interlocking clutch adapted to lock the parts together at any rotative position of the platen relative to the line space wheel.

A platen release of this character will be 25 found in the patent to Arthur W. Smith, No. 860,834 of July 23, 1907, but the object of my invention is to simplify the construction and to so condense and arrange the parts that the entire device may be mounted 30 on the end of the platen shaft; none of the parts being located inside the end of the platen.

My device, while adaptable to typewriting machines of various types is more particularly designed for and is shown in connection with the platen of the well known 35 Underwood typewriter.

One form of my device is shown in the accompanying drawings, in which only fragmentary parts of the typewriter platen and carriage are shown.

Figure 1 is a plan view partially in section; Fig. 2 is substantially a complete longitudinal section; Fig. 3 is a plan view and 45 partial section looking at the opposite side from that shown in Fig. 1; Fig. 4 represents a cross section at 4-4 of Fig. 1, and Fig. 5 shows one of the wedge members.

Referring to the drawings 1 represents a 50 portion of the typewriter platen carriage of the well known Underwood machine in which one end of the platen 2 is pivoted by means of the axle 3 which extends therethrough. The end plate of the platen carriage 1 is provided with the usual detent

roller 4 which is spring pressed against the line space wheel by the spring 5 in the usual or any preferred manner; these parts being the regular construction. In the present instance in carrying out my invention the axle 60 or shaft 3 to which the platen 2 is secured, by the screw 2^a, extends into the end of a tubular hub 6 which is pinned to the end of the shaft at 7 and adapted to rotate therewith. This tubular hub is provided with a 65 cupped or flanged disk 8 concentrically arranged adjacent to the bearing 1^a, in the platen carriage frame, through which the axle of the platen passes. The flanged disk 8 is adapted to support on its periphery an 70 annular line space wheel 9 which, as indicated in the drawings, is provided with an internal flange adapted to seat in a corresponding angle groove 10 in the edge of the disk 8. The opposite side of the line space 75 wheel 9 is provided with an annular ring flange 11 in which an annular toothed ring 12 is seated and is securely held in place by suitable pins or screws 13, the construction 80 being such that the line space wheel 9 is held 85 in place on the periphery of the flange 8, but is free to rotate thereabout. The annular ring 12 is provided with one or more inwardly projecting teeth 14 which, as indicated in the drawings, are wedge shaped on 90 their inner side and thereby adapted to freely enter the corresponding tooth spaces in a spur-toothed clutch member 15, which, as indicated, is provided with a plurality of 95 straight teeth which have their lateral edges beveled off, as indicated, so as to facilitate co-operation with the beveled faces of the teeth 14. The teeth of both clutch members are therefore provided with straight faces and beveled faces, the beveled faces on each 100 coming together in a thin edge so that the teeth of one member will readily enter between those of the other. When the clutch members are in complete engagement the straight portions of the teeth are in contact 105 and hence there can be no slipping of one member with respect to the other. The tooth clutch member 15 is provided with a hub 16 which is loosely mounted on the cylindrical hub 6 which, as previously explained, is secured to the end of the platen axle. The disk 8 on the hub 6 as indicated is hollowed out and is of sufficient diameter to receive therein the clutch member 15, when the same is pressed or forced toward 110

- the right as viewed in the drawings. A compression spring 17 is placed between the disk 8 and clutch member 15 and is adapted to normally exert pressure upon and hold 5 the clutch member in the position indicated in Figs. 1 and 2 of the drawings, in which position the clutch teeth 14 of the annular ring 12 interlock with the clutch teeth of the clutch member 15.
- 10 The clutch member 15 is both slidably and revolvably mounted upon the hub 6, but the amount of movement circumferentially is limited to slightly more than the distance between two consecutive teeth of the clutch 15 member 15. The object of this lateral or circumferential movement, it will be understood, is for the purpose of permitting the clutch members to come into complete engagement irrespective of the relative position 20 of the platen and line space wheel. The clutch teeth 14, as previously explained, are secured to the line space wheel, while the clutch member 15 mounted on the hub 6 is adapted to be secured to the platen as hereinafter 25 explained, thereby permitting the platen and line space wheel to revolve in unison, when the clutch members are in interlocking position, as indicated in Figs. 1 and 2 of the drawings.
- 30 In order to secure the movable clutch member to the hub 6 and consequently to the platen in any rotative position of the latter the amount of circumferential movement of the clutch member 15 is, as previously 35 stated, limited, and wedge members 18 are provided for positively securing the clutch member 15 to the hub 6. The hub 16 as indicated in Fig. 1 of the drawings is provided with oppositely disposed elongated 40 openings 19, one edge of each opening being at an angle to the axis so as to form inclined planes or wedging faces 20, against which faces the wedged lugs 21 secured to and extending from the ends of the wedge members 18 into the openings 19 are adapted to contact, and thus secure the clutch member 15 in its adjusted position relative to the hub 6. The hub 6 secured to the platen axle, is provided with longitudinal slots or 45 grooves 22 in which the clutch members 18 are adapted to slide in order to accommodate the wedge lugs 21 thereof to the wedging faces 20, according to the position of adjustment of the clutch member 15. It 50 will be understood that the wedge or cam faces 20, on opposite sides of the hub 16, face in opposite directions circumferentially or lie in substantially the same vertical planes, so that when the clutch member 15 55 is in its central position as to circumferential adjustment, the wedge members 18, with their wedging lugs 21, will lie substantially opposite each other throughout their length and the wedge members 21 will be practically 60 at the middle of the cam or wedge

faces 20. If, however, the clutch member 15, in coming back into engagement with the clutch teeth 14, is forced to the one side or the other of its central position, then one of the wedge faces 20 will be further away 70 from its corresponding cam lug 21 than the other, with the result that it will be necessary for one wedge to slide farther than the other in order to permanently lock the clutch member in the adjusted position. It 75 will be observed that in Fig. 2 the ends of the wedge members 18 are not directly opposite, indicating that in the adjustments shown in the drawings the clutch member 15 is turned a small amount to the one side of 80 its central position, but the independent movement of the wedge members 18 has enabled the wedges 21 to follow the respective wedge faces 20 and lock the clutch member in the position indicated. In order to get 85 this variable adjustment of the wedge member 18, the inner edges of the wedge carrying members 18 are provided, in the present instance, with gear teeth 23 which are adapted to mesh with a pinion 24 pivoted in the slotted end of the plunger 25 which is adapted to reciprocate in the end of the tubular hub 6 and is normally pressed outwardly by a spring 26 which thrusts against the end 90 of the axle 3, as indicated in Fig. 2 of the 95 drawings. It will be seen that this arrangement of rack and pinion connection between the wedge members 18 permits independent movement of the wedge members whereby they are adapted to accommodate themselves to the varying requirements according to the rotative position of adjustment of the clutch member 15 relative to the hub 6 when the teeth of the clutch member are in engagement with the clutch teeth 14 carried 100 by the line space wheel. The plunger 25 is preferably extended beyond the end of the hub 6 and is provided with a push button 27 which may be secured thereto in any suitable manner as by screw threads 27^a shown 105 in Fig. 1 of the drawings. The usual finger wheel 28 is, in the present instance, provided with a hub 29 secured thereto in any suitable manner as by being pinned to the flange 30, the hub 29 extending laterally over the 110 hub 6 and being secured thereto by suitable screws 31, as indicated in Figs. 1 and 3 of the drawings. Preferably the hub 29 of the finger wheel is of sufficient length to serve as a stop or limiting means to determine the 115 outward movement of the clutch member 15 under the pressure of its spring 17.

The wedges 21 of the wedge members 18, as indicated in the drawings, extend outward into the openings 19 in the hub 16 of 120 the clutch member 15 and the ends of the wedges 21 are squared off and adapted to contact with the ends of the open slots 19, adjacent to the clutch member 15 and serve 125 to thrust the same backward against pres- 130

sure of the spring 17 and disengage the clutch teeth of the clutch member from the clutch teeth 14 of the line space wheel 9. This position of disengagement of the clutch member 15 is indicated in Fig. 3 of the drawings, in which position the platen may be rotated independently of the line space wheel. When in this disengaged position it is desirable that the clutch member 15 be positioned or centered with respect to its latitude of rotary movement one side or the other of the normal position, in order that it may readily accommodate itself to any new position of relative rotation between the platen and line space wheel which may occur when the platen is rotated independently of the line space wheel for any new setting thereof. To centralize the clutch member 15, any suitable means may be employed, but I have shown the simple device of a screw 32 secured to the hub 6 and projecting therefrom into a triangular or V-shaped opening 33 in the hub 16, the position of the V-faces being such that the clutch member 15 may be pushed entirely into the pocket in the disk 8 and thereby freed from the teeth 14 when the screw 32 arrives at the bottom of the V, as indicated in Fig. 3 of the drawings. Thus it will be seen that from either position of adjustment one side or the other of the central position the clutch member 15 will always be brought back into a central normal position when disengaged from the coöperating clutch teeth of the line space wheel.

Normally the clutch member and wedging members are in the position indicated in Figs. 1 and 2, but when the operator desires to release the platen from the line space wheel for any adjustment of the former with respect to the latter, the finger button 27 is pressed inwardly into the position as indicated in Fig. 3 of the drawings, in coming to which position the wedge members 18 and 21 will first be forced inwardly away from the wedge faces 20 and release the clutch member 15, the end of the wedges 21 then striking against the ends of the openings 19 will thrust the clutch member 15 back to the position of disengagement or into the pocket in the disk 8, as indicated in Fig. 3 of the drawings, thus releasing the platen for independent rotation. During this operation the faces of the triangular or V-shaped opening 33 will, by means of the screw 32, centralize the clutch member 15, so that upon releasing the button 27, the springs 17 and 26 will thrust out the respective parts and reengage the clutch members so that the platen and line space wheel are locked together to revolve in unison.

It will be understood that various modifications of details of construction in the form of the device here shown may be resorted to without departing from the spirit and

scope of the invention as defined in the claims.

I claim:

1. In a typewriter platen release the combination of a platen, a line space wheel, clutch teeth on said line space wheel, a toothed clutch member adjustably connected with the platen and adapted to coöperate with the clutch teeth of the line space wheel, and a pair of independently movable wedge members adapted to secure said toothed clutch member in adjusted position when in mesh with the clutch teeth of said line space wheel thereby connecting the line space wheel and platen to be revolved in unison.

2. In a typewriter platen release the combination of a platen, a line space wheel, clutch teeth on said line space wheel, a movable, toothed clutch member provided with a pair of wedge faces, a pair of independently movable wedge members adapted to coöperate with the wedge faces on said clutch member, and means for releasing said wedge members and moving said clutch member to connect and disconnect the platen and line space wheel.

3. In a typewriter platen release the combination of a platen secured to an axle, a line space wheel revolubly mounted on said axle, clutch teeth on said line space wheel, a movable clutch member adapted to coöperate with the clutch teeth of said line space wheel, said clutch member being adjustable to a limited extent either way from a central position, fixed means for centralizing said clutch member after disengaging the same from said line space wheel and means for moving said clutch member to disengage the same and thereby permit the platen to be rotated independently of said line space wheel.

4. In a typewriter platen release the combination of a platen, a tubular hub member connected with the platen, a line space wheel mounted thereon, clutch teeth projecting from the line space wheel, a coöperating clutch member also mounted on said hub member in axial alinement with and movable toward and from said line space wheel, means permitting a limited rotary movement of said clutch member to engage the clutch teeth of the line space wheel in any rotative position of the latter with respect to the platen and means connected with the platen through said hub member for preventing movement of said clutch member when in engagement with the clutch teeth of said line space wheel, thereby securing the platen and line space wheel together to revolve in unison.

5. In a typewriter platen release the combination of a platen secured to an axle, a tubular hub secured to the end of said axle, a concentric disk on said hub about which said line space wheel is adapted to revolve,

clutch teeth projecting from said line space wheel, a coöperating clutch member slidably and circumferentially movable upon said tubular hub and provided with wedge faces, 5 independently movable wedge members slidably longitudinally of said tubular hub and adapted to coöperate with said wedge faces, and means for sliding said wedge members and said clutch member to connect the line 10 space wheel and platen to revolve in unison or to disconnect the same so that the platen may be revolved independently of said line space wheel.

6. In a typewriter platen release the combination of a platen, a line space wheel provided with clutch teeth, a movable clutch member adapted to coöperate with the clutch teeth of said line space wheel, means for securing said clutch member when in engagement with the clutch teeth of said line space wheel, said means including a pair of independently slideable wedge members, a spring for moving said members in one direction, a manually movable member against which 20 said spring is adapted to thrust and intermediate means carried by the last named member for equalizing the pressure of the spring on said sliding wedge members.

7. In a typewriter platen release the combination of a platen, a line space wheel and means for securing the two together at any rotative position of one with respect to the other comprising interlocking clutch members one of which is movable with respect to 30 the other, a spring for moving said movable clutch member in one direction, a pair of slideable wedging members for preventing movement of the movable clutch member when the clutch members are in engagement said slideable wedging members during disengagement being adapted to move said movable clutch member in opposition to its spring, a spring for sliding said wedging members in one direction and manually operable 40 means for moving said wedging members and said movable clutch member in succession in opposition to their respective springs to release said clutch and permit rotation of the platen independently of said line space 50 wheel.

8. In a typewriter platen release the combination of a platen, a line space wheel provided with clutch teeth, an axle support therefor, connected with the platen, a co- 55 operating clutch member slidably upon said support into and out of engagement with the clutch teeth of said line space wheel, said clutch member being also circumferentially adjustable relative to the platen and means for securing said clutch member in 60 adjusted position when in engagement with said clutch teeth of the line space wheel thereby connecting the platen and line space wheel to revolve in unison.

65 9. In a typewriter release the combina-

tion of a platen secured to an axle, a line space wheel, a hub member secured to the axle of the platen, a disk integral with said hub member and adapted to revolubly support said line space wheel, clutch teeth secured to said line space wheel, a coöperating toothed clutch member slidably mounted upon said hub member and permitted a limited circumferential movement and means projecting through said hub member for locking said clutch member when in coöperative engagement with the clutch teeth of 70 said line space wheel.

10. In a typewriter release the combination of a platen secured to an axle, a line 80 space wheel, a hub-like member secured to the axle of the platen, a disk integral with said hub member and provided with an overhanging rim adapted to revolubly support said line space wheel, clutch teeth secured 85 to said line space wheel, a coöperating clutch member comprising a spur toothed disk having a hub slidably and revolubly mounted upon said hub-like member and means mounted in said hub-like member co-acting 90 with said clutch member to lock the same against independent movement when in coöperative engagement with the clutch teeth of the line space wheel, the disk of the clutch member, when disengaged from the line 95 space wheel, being adapted to enter the pocket formed by the rim on the hub disk.

11. In a typewriter release the combination of a platen secured to an axle, a line space wheel, a hub-like member secured to 100 the axle of the platen, clutch teeth on the line space wheel, a coöperating clutch member, slidably mounted upon said hub-like member, said clutch member having a hub provided with wedge shaped slots therein 105 and wedging members slidably mounted in said hub-like member adapted by coöperation with said slotted hub, to lock said clutch member against independent movement when in engagement with the clutch 110 teeth of the line space wheel.

12. In a typewriter release the combination of a platen secured to an axle, a line 115 space wheel, a hub-like member secured to the axle of the platen, clutch teeth on the line space wheel, a coöperating clutch member slidably mounted upon said hub-like member, said clutch member having a hub provided with wedge shaped slots therein, 120 wedging members slidably mounted in said hub-like member adapted by coöperation with said slotted hub, to lock said clutch member against independent movement when in engagement with the clutch teeth of the line space wheel and a push button adapted 125 to release said wedging members and disengage said clutch member in succession.

13. In a typewriter release the combination of a platen secured to an axle, a line 130 space wheel, a hub-like member secured to

the axle of the platen, clutch teeth on the line space wheel, a coöperating clutch member slidably mounted upon said hub-like member, said clutch member having a hub 5 provided with wedge shaped slots therein, a spring acting upon said clutch member to cause its engagement with the clutch teeth of said line space wheel, wedging members slidably mounted in said hub-like member 10 and adapted to coöperate with the slots in the hub of said clutch member to lock the same against independent movement when in engagement with the clutch teeth of the line space wheel and a spring acting to move 15 said wedging members into wedging position.

14. In a typewriter release the combination of a platen secured to an axle, a line space wheel, a hub-like member secured to 20 the axle of the platen, clutch teeth on the line space wheel, a coöperating clutch member slidably mounted upon said hub-like member, said clutch member having a hub provided with wedge shaped slots therein, 25 a spring acting upon said clutch member to cause its engagement with the clutch teeth of said line space wheel, wedging members slidably mounted in said hub-like member and adapted to coöperate with the slots in 30 the hub of said clutch member to lock the same against independent movement when in engagement with the clutch teeth of the line space wheel, a spring acting to move 35 said wedging members into wedging position, and manually operable means for releasing said wedging members and moving said clutch member in succession to disen-

gage the latter from said line space wheel, both of said springs being compressed thereby. 40

15. In a typewriter release the combination of a platen secured to an axle, a line space wheel, a hub-like member secured to the axle of the platen, clutch teeth on the line space wheel, a coöperating clutch member 45 slidably mounted upon said hub-like member, said clutch member having a hub provided with wedge shaped slots therein, a spring acting upon said clutch member to cause its engagement with the clutch teeth 50 of said line space wheel, wedging members slidably mounted in said hub-like member and adapted to coöperate with the slots in the hub of said clutch member to lock the same against independent movement when 55 in engagement with the clutch teeth of the line space wheel, a spring acting to move said wedging members into wedging position, intermediate means between said wedging members for equalizing the pressure of 60 said spring and manually operable means connected with said intermediate means for releasing said wedging members and moving said clutch member, in succession, to disengage the latter from said line space 65 wheel, both of said springs being compressed.

In testimony whereof, I have hereunto set my hand in the presence of two subscribing witnesses.

MARQUIS H. LOCKWOOD.
